HYGROMETER

Anthony H. Lamb, Hillside, N. J.

Application October 11, 1945, Serial No. 621,784

5 Claims. (Cl. 73—335)

1

This invention relates to hygrometers, and more particularly to direct reading instruments for the measurement of relative humidity.

The direct reading hygrometers now manufactured commercially are based upon the longitudinal expansion of strands or strips of organic material upon an increase in the absorbed water or water vapor at increasing relative humidity. Such hygrometers are reasonably satisfactory when located in an air conditioned space in which they are subjected to only small changes in relative humidity and when restandardized from time to time to compensate for changes in the length and the strength of the strands or strips as they age. The organic material may be human hair, paper or wood but is usually human hair. Although the gradual drift in calibration of such organic materials is well known, it is not so generally known that there is a marked lack of uniformity even in supposedly identical hair type hygrometers manufactured by the same company, and that it is not possible to obtain identical operating characteristics by standardizing a series of such hair type hygrometers at any one relative humidity. Furthermore, standardization at any particular relative humidity will not be maintained even at that humidity value as the length and strength of the strands of hair will change with time.

The known deficiencies of the hygrometers with longitudinally extensible strands or strips of organic material have resulted in proposals for electrical types of hygrometers, and such apparatus may be satisfactory for laboratory use but it is too expensive, bulky and complex for incorporation in small or portable hygrometers. It was also proposed, nearly a century ago, to measure relative humidity by a balance having non-hygrosopic and hygroscopic masses located at opposite sides of the axis of the balance system. Such balance systems presumably were even less satisfactory than the extensible strand or strip type of hygrometer and, so far as known, were never manufactured commercially.

According to the present invention, the known disadvantages of the hygrometers with extensible strips or strands of organic material are avoided by weighing the water or water vapor content of an absorbent or adsorbent material that is not tensioned or otherwise stressed. The absorbent or adsorbent material may be a solid or a liquid, or mixtures of solids and/or liquids, which are not affected chemically by water and which have the reversible property of taking up and giving off water in accordance with changes in the rela-

2

tive humidity of the atmosphere to which they are exposed. Solid non-organic adsorbents are preferable for small and/or portable hygrometers, but either solids or liquids may be employed in hygrometers of any desired size and of portable or stationary type. Liquids such as triethylene glycol, lithium chloride or iodide or calcium chloride may be held in a porous or fibrous mass of organic or inorganic material.

5 The carrier mass may be either hygroscopic or non-hygrosopic. The weight of the adsorbed water or water vapor is directly measured against a coiled spring that tends to displace a pointer along an arcuate scale graduated in relative humidity; the direct measurement being obtained by balancing the "dry" weight of the absorbent by the weight of a non-hygrosopic mass.

An object of the present invention is to provide direct reading hygrometers that may be accurately calibrated and that maintain their calibration over wide ranges of relative humidity and over long periods. An object is to provide hygrometers of the direct reading type in which the pointer is displaced along a graduated humidity scale by the weight of the water or water vapor content of an adsorbent material. An object is to provide a hygrometer in which a pointer is mounted upon a horizontally disposed shaft, an adsorbent mass and a non-hygrosopic mass are mounted at opposite sides of the shaft, and a coiled spring tends to turn the shaft and pointer in opposition to the torque exerted thereon by the water or water vapor held by the adsorbent mass. More specifically, an object is to provide a direct reading hygrometer in which a coiled spring tends to displace a pointer along an arcuate scale graduated in values of relative humidity, and the spring action is opposed and balanced by the weight of the water or water vapor of an adsorbent material having the characteristic of substantially constant size and shape as it takes up and gives off water or water vapor in accordance with the relative humidity of the atmosphere to which the adsorbent material is exposed.

These and other objects and the advantages of the invention will be apparent from the following specification when taken with the accompanying drawing in which:

50 Fig. 1 is a front elevation of the essential elements of a humidity indicator embodying the invention;

Fig. 2 is a side elevation of the same;

Fig. 3 is a fragmentary front elevation, on a larger scale, of an instrument balance system

in which the activating material is of powder or granular form within an apertured container;

Fig. 4 is a side elevation of the scale plate and moving system of another embodiment;

Fig. 5 is a front elevation of the same; and

Fig. 6 is a front elevation, with parts broken away, of a multiplier type of instrument embodying the invention.

In Figs. 1 and 2, the reference numeral 1 identifies a staff or shaft which is pivotally supported for angular movement by jewel bearings 2 carried by a bracket 3. A pointer assembly such as commonly employed in electrical measuring instruments is mounted on the staff 1, the assembly comprising a pointer 4, threaded cross arms 5, 6 and a tail 7. The pointer 4 is movable along the arcuate scale 8 of relative humidity values which is printed or otherwise formed on the scale plate 9. A small block 10 of a hygroscopic material which remains solid and dry even at 100% relative humidity is supported on the cross arm 5, the block 10 being held within a wire cage constituted by the expanded turns of a spring 11 having a closely coiled end 12 threaded upon the cross arm. The dry weight of the piece 10 of hygroscopic material is balanced by a non-hygroscopic counterweight 13 adjustably threaded on cross arm 6, and displacement of the staff 1 and pointer 4 is opposed by a coiled spring 14 having an inner end fixed to the staff 1 and an outer end adjustably anchored on the bracket 3 by an arm 15. For portable instruments, the tail 7 of the pointer assembly preferably merges into an arcuate vane 16 which moves within the air gap of a damping magnet 17.

The material 10 may be one of, or a mixture of, any of the solid dry absorbents or adsorbents which vary in weight with the relative humidity to which they are exposed, or may be a porous body or a fibrous mass impregnated or partially impregnated with a liquid which takes up and gives off water as a function of relative humidity. A number of the inorganic materials now sold commercially under various trade-marks as absorbents or adsorbents are suitable, for example silica gel, bauxite or activated bauxite, aluminum trihydrate and the like. Other substances may be mixed with the absorbent material or materials to modify the relative humidity-adsorbed water characteristic of the mass.

The adsorbent material may be in powder or granular form to decrease the time lag between a change in relative humidity and the resultant change in the weight of the material as it takes up or gives off water for equilibrium at the new humidity value. As shown in Fig. 3, a granular mass 10' of adsorbent material or of porous material saturated or partially saturated with a water-absorbing liquid may be held in a small annular cage comprising a threaded sleeve 18 for mounting the cage on the cross arm 5 of the pointer assembly, a base 19, and a foraminous cup 20 made up from screen material of relatively small mesh secured to the sleeve 18 and base 19.

Various arrangements may be employed to support the adsorbent material and a counterbalance weight at opposite sides of the pointer staff. As shown in Figs. 4 and 5, a shallow semi-cylindrical cage 21 for holding powdered or granular adsorbent material 10', and a complementary semi-cylindrical balance weight 22 are mounted on the staff 23 which is supported in bearings, not shown, and provided with a calibration spring 24. A pointer 25 on the staff 23 moves along the

graduated scale 26 on the annular scale plate 27. Alternatively, the annular scale plate could be supported on the staff 23 for movement of the graduated scale 26 with respect to a fixed pointer or index mark. The casing in which the moving system and scale plate are mounted may be a close-fitting circular casing, or it may be of any desired larger size and shape.

The scales of the direct reading hygrometers 10 could be individually marked and graduated for each instrument, but that additional expense of manufacture is not necessary since pre-printed graduated scales may be used when the "weighing" springs of the instruments are of at least 15 approximately the same strength. The volume or mass of the adsorbent material is not critical when, as described, the instruments include means for adjusting the adsorbent material towards and away from the pivotal axis to vary 20 the effective torque arm of the water or water vapor held by the adsorbent material. Such adjustments and similar adjustment of the effective torque arm of the non-hygroscopic balance weight 25 permit an accurate matching of the measured humidity values to a pre-printed scale graduated in relative humidity values.

The scale graduations of the instruments illustrated in Figs. 1 and 5 are non-uniform as a full scale displacement of the pointer requires such 30 large angular displacement of the adsorbent material that there is a substantial change in the effective lever or arm of the adsorbed water or water vapor. A more nearly uniform graduation of an elongated scale may be had by coupling the 35 balance system to the pointer through a motion-multiplying gearing, thereby reducing the angular movement of the adsorbent material.

A typical construction, as shown in Fig. 6, includes a cup 20' containing adsorbent material 40 and adjustably threaded upon the outer end of a lever 28 which is secured to a staff 29. Bearings, not shown, support the staff on a bracket 30, and a coiled spring 31 is secured to the staff and the bracket respectively. An arcuate gear 32 at the inner end of the lever 28 meshes with a pinion 33 on staff 34 which carries the pointer 35. The gear ratio may be of any desired value but is preferably such that the graduated scale 36 of about 45 300° extent corresponds to an angular movement of the adsorbent material of about 20° to opposite sides of its horizontal position.

It is to be understood that the invention is not limited to the particular constructions herein 50 shown and described as various changes fall within the spirit of the invention as set forth in the following claims.

I claim:

1. A direct reading hygrometer comprising a 60 horizontally disposed staff, side arms secured to and extending in opposite directions outwardly from said staff, a mass of hygroscopic material mounted on one of said side arms and adjustable along the arm axis, a mass of non-hydroscopic material mounted on the other side arm and likewise adjustable along the arm axis, a spring opposing angular rotation of said staff by the water vapor content of the hygroscopic material, a pointer member cooperative with said staff and rotatable therewith and a stationary graduated scale cooperative with said pointer member.

2. A direct reading hygrometer as defined in 70 claim 1 wherein said hygroscopic material is disposed within a containing member and said containing member open to the surrounding air is

carried by and adjustable along the axis of the associated side arm.

3. A direct reading hygrometer as defined in claim 1 wherein the hygroscopic material is constituted by a single body disposed within a wire cage and said cage is carried by and adjustable along the axis of the associated arm.

4. A direct reading hygrometer as defined in claim 1 wherein said hygroscopic material is of granular form contained within a foraminous cup carried by and adjustable along the axis of the associated side arm.

5. A direct reading hygrometer comprising a horizontally disposed staff, a pointer secured to said staff and having oppositely extending side arms, a mass of hygroscopic material mounted on one of said side arms and adjustable along the arm axis, a mass of non-hygroscopic material mounted on the other side arm and likewise ad-

justable along the arm axis, a spring opposing angular rotation of said staff by the water vapor content of said hygroscopic material, and a graduated scale cooperative with the said pointer.
